US00D897000S

(12) **United States Design Patent** (10) **Patent No.:** **US D897,000 S**
(45) **Date of Patent:** ** *Sep. 22, 2020

(54) **FLOORING MEMBRANE**

(71) Applicants: **Svein Julton**, Tinn Austbydge (NO);
Joe Comitale, Mississauga (CA)

(72) Inventors: **Svein Julton**, Tinn Austbydge (NO);
Joe Comitale, Mississauga (CA)

(*) Notice: This patent is subject to a terminal disclaimer.

(**) Term: **15 Years**

(21) Appl. No.: **29/591,162**

(22) Filed: **Jan. 17, 2017**

(57) **CLAIM**

The ornamental design for a flooring membrane, as shown and described.

DESCRIPTION

FIG. 1 is a top isometric view of a flooring membrane showing our new design.

FIG. 2 is an enlarged isometric view of encircled area 2 of FIG. 1, rotated slightly.

FIG. 3 is a sectional view of the structure of FIG. 2 taken from opposing corners and rotated slightly; and,

FIG. 4 is an enlarged isometric view of encircled area 4 of FIG. 1, rotated slightly.

1 Claim, 4 Drawing Sheets
